PLASTIC DRUM

Enrico Crosio, Milan, Italy, assignor of one-third each to Pirelli Societa per Azioni, Milan, Italy, Montecatini Societa Generale per l'Industria Mineraria e Chimica, Milan, Italy, and Plax Corporation, West Hartford, Conn.

Application March 6, 1956, Serial No. 40,483

Term of patent 14 years

(Cl. D58—17)

FIG. 1

FIG. 2

FIG. 3

Fig. 1 is a top plan view of a plastic drum, embodying my new design;

Fig. 2 is a front elevation view thereof, and

Fig. 3 is a fragmentary cross-sectional view thereof, taken on the line 3—3 of Fig. 1.

I claim:

The ornamental design for a plastic drum, as shown.
